CLAIM

The ornamental design for a display device, as shown and described.

DESCRIPTION

FIG. 1 is a perspective view of a display device; FIG. 2 is a front view of the display device, with the rear view, the left side view, and the right side view being mirror images thereof;

FIG. 3 is a top view of the display device, with the bottom view being a mirror image thereof; and,

FIG. 4 is a perspective view of the display device with an image, such as icons, displayed thereon, the image forming no part of the claimed design.

The broken lines shown in the drawings illustrate portions of the display device that form no part of the claimed design.
